ELECTRONIC TRIGGER CIRCUIT

Horatio N. Crooks, Haddonfield, N. J., assignor to
 Radio Corporation of America, a corporation
 of Delaware

Application September 28, 1951, Serial No. 248,839

6 Claims. (Cl. 315—168)

1

This invention relates to bistable state electronic circuits and more particularly to circuits of the type including a gaseous electron discharge tube which may be switched between two stable conditions.

Two tube bistable state circuits, such as the Eccles-Jordan trigger circuit found described on page 54 of "Time Bases" by O. S. Puckle published by John Wiley and Sons, Inc., are well known. These types of circuits have two stable limiting conditions and are driven from one state to the other by externally applied pulses. The two tubes are alternately driven from a conducting to a non-conducting state by pulses of a given polarity being applied, although a two tube bistable state circuit may be used to control or provide an output to a single circuit with successively applied pulses of one polarity. In this event, one of the two tubes, although required for circuit operation, is not performing any output function. A bistable state circuit which employs only a single tube is more economical for such an application, since both power and circuit component requirements are reduced.

It is an object of the present invention to provide a novel bistable state circuit employing a single tube.

It is a further object of the present invention to provide an improved and inexpensive single tube bistable state circuit.

Still another object of the present invention is to provide a bistable state circuit employing a single gas tube.

In a copending application of E. O. Johnson, Serial No. 185,745, filed September 20, 1950, and assigned to the assignee of the present invention, there is described and claimed a gaseous electron tube in which current drawn through the work circuit of the tube may be controlled at all times despite the fact that the tube is ionized. This is performed by providing one source for the tube ionizing current and a second source for the tube work current. By using a separate electrode and a separate source for maintaining the ionizing current, a plasma is generated which surrounds the anode and cathode of the gaseous tube, and since this plasma (an equal mixture of ions and electrons) is a fairly good conductor, it prevents the formation of a space charge around the cathode. This prevents a space-charge limiting effect and, because the plasma has such a low resistance, a relatively large current may be drawn from the cathode with only a few volts applied between cathode and anode. Furthermore, as long as the anode voltage does not ex-

2

ceed the ionizing potential of the gas, the tube can be operated either as a triode, in which case the plate current can be controlled continuously by the grid voltage, or as a diode, in which case the grid is tied to the plate and the plate current can be controlled by controlling the auxiliary discharge current.

Control of the plate current by the grid voltage of this tube is made possible because of the fact that changes in thickness of the positive ion sheaths about the grid wires occur as the grid voltage is varied. The sheaths restrict the plasma cross section and control its electrical resistance and thus control the plate current.

Control of the plate current by controlling the auxiliary discharge current is possible because of the fact that the plate current is proportional to the density of ionization which in turn is proportional to the auxiliary discharge current.

The objects of this invention are achieved by employing a gaseous electron tube, of the type described in detail in the aforesaid application by Johnson, in a circuit wherein a potential having a value less than ionization potential is applied between a main cathode and anode of the tube and a potential having a value between ionizing and extinction potential is applied between the main and auxiliary cathodes of the tube. In response to pulses of one polarity being successively applied to the main cathode, control grid and auxiliary cathode, the tube is rendered alternately conducting and non-conducting responsive to these pulses.

The novel features of the invention, as well as the invention itself, both as to its organization and method of operation will best be understood from the following description when read in connection with the accompanying drawings, in which:

Figure 1 is a cross section of a gaseous electron discharge tube used in the embodiments of the present invention.

Figure 2 is a circuit diagram of one embodiment of the invention, and

Figure 3 is a circuit diagram of a second embodiment of the invention.

Referring now to Figure 1 of the drawing, there may be seen a cross section of a gas tube 10 used in the embodiments of the invention having a structure essentially such as is described in the above mentioned copending Johnson application. Since details of the tube structure form no part of the present invention, in and of themselves, the tube will be described herein only briefly.

The tube has a tube envelope 10 which encloses

the following electrodes. A U-shaped anode 12 encloses a control grid and a main cathode 16. Opposite the open end of the U-shaped anode 12, there is provided an auxiliary cathode 18 which is surrounded by a constricting electrode 20. The constricting electrode has a narrow slit 22 therein extending its full length and positioned opposite the main cathode 16.

The operating characteristics of the tube are such that when a voltage greater than the ignition voltage of the tube gas is applied, either between the auxiliary cathode 18 and the main cathode 16, or between the auxiliary cathode and the anode 12 or both, the tube gas becomes ionized and current flows from the auxiliary cathode to ionize the tube gas. In ionizing the tube gas an "ion-electron-plasma" is provided which serves as a conductor of current between the main cathode and the anode. This current is obtained with a voltage having a much lower value than that required to ionize the tube gas. This "lower than ionization value" potential may be supplied by a battery (not shown) connected between the anode and the main cathode. A grid 14 consisting of grid wires widely spaced and positioned close to the anode surface serves as a control grid and can continuously control the amount of current which is permitted to flow between the anode and the main cathode.

The slot in the constricting electrode normally functions to concentrate the ionizing current so that a relatively small quantity thereof can provide relatively high plasma densities.

Referring now to Figure 2, a gaseous electron tube 10 such as has been described is utilized, together with connections and circuit components to provide a bistable trigger circuit. A source of potential 23 is connected between the main cathode and the anode through a load resistor 24. This potential source 23 has a value less than the required ignition or ionizing potential for the tube gas. A pair of input terminals 26 are provided to which negative pulses may be successively applied. The main cathode 16 and the auxiliary cathode 18 have applied to them a potential which is between ionization and extinction potential for the tube gas. This potential source is represented by the battery 28 with a potentiometer 30 positioned thereacross for determining or setting this potential. The main cathode 16 is biased positively with respect to the auxiliary cathode 18. A differentiating circuit 32 couples the input terminals to the auxiliary and main cathodes. This differentiating circuit consists of a resistor 34 across the input terminals 26 and a condenser 36 between one of the input terminals and the auxiliary cathode 18. The main cathode 16 is connected to the other of the input terminals. A resistor 38 and a condenser 40 connected in parallel are connected between the control grid 14 and the main cathode 16. In operation, negative pulses when successively applied to the input terminals 26 serve to change the tube from a conducting to a non-conducting condition alternately. Output is derived from the terminals 42 connected to the anode 12.

A complete explanation of what occurs is not precisely known. However, it is believed that when a negative signal pulse is applied to the input terminals 26, the pulse is differentiated by the differentiating circuit 32 and a negative pulse is applied thereby to the auxiliary cathode 18 as a result of the front end of the signal pulse and a positive pulse is applied to the auxiliary

cathode at the termination of the signal pulse as a result of the trailing end of the input pulse. The negative pulse tends to send the tube into conduction, the positive pulse tends to send it out of conduction. However, when the tube is sent into conduction a certain amount of time is required for the gas discharge or ionization current to build up, during which time the voltage between cathodes drops. If the positive going pulse occurs before this voltage between cathodes has dropped too far, the pulse will not extinguish the discharge. If, however, the positive pulse appears after the auxiliary discharge current has built up and the voltage between cathodes has dropped sufficiently, the pulse will extinguish the discharge. Thus, if a negative signal pulse is applied to the tube when in the state of conduction, the negative pulse has no effect on the discharge but the positive pulse turns it off.

Whatever the correct explanation for the operation of the circuit may be, it has been definitely established by actual construction of the circuit that it operates in response to negative pulses as described. Values for one embodiment of the invention which has been constructed and operated are provided below.

These values are not to be taken as a limitation upon the invention, since the circuit can function with other circuit component values as well. The values are being furnished merely as an illustrative embodiment of this invention.

Resistor 24, 5,000 ohms
Resistor 34, 13,000 ohms
Resistor 38, 220,000 ohms
Condenser 36, 0.25 mmf.
Condenser 40, 0.05 mmf.
Battery 23, 16 volts
Battery 28, 90 volts
Potentiometer 30, 5,000 ohms
Input pulse, 45 volts amplitude

Reference is now made to Figure 3 which shows a circuit diagram of a second embodiment of the present invention. Here also a potential 23 having a value below that required for ionization of the gas in the tube is applied through a load resistor 24 between the anode 12 and tube main cathode 16. A second potential 44 is provided between the main 16 and auxiliary cathodes 18 by a battery 41 shunted by a potentiometer 46, as was previously explained, to obtain a potential having a value between that required for ignition and extinction of the tube gas. A pair of pulse input terminals 26 are provided with a differentiating circuit 48 connecting the input terminals to the main 16 and auxiliary cathodes 18. This differentiating circuit 48 consists of a first resistor 50 connected across the terminals 26 and a condenser 52 connected from one of said terminals to the auxiliary cathode. A condenser 54 also connects the same one of the input terminals to the control grid 14. A second resistor 56 is connected between the control grid 14 and the main cathode 16 of the tube. The constricting electrode 20 is also connected to the auxiliary cathode.

When positive pulses are successively applied to the input terminals 26, the tube 10 switches from conduction to non-conduction alternately in response to the successive pulses. A specific explanation for the operation of this circuit is also not completely known. However, it is thought that the positive input pulses which are applied to the input terminals appear on both

the control grid and the auxiliary cathode. The pulse appearing on the grid is of such a polarity as to increase the voltage drop existing between the grid and the auxiliary cathode and to tend to turn the tube on. The pulse appearing on the auxiliary cathode is of such a polarity as to decrease this voltage drop and to tend to turn the tube off.

Although the initial pulse height is the same on both electrodes, the time constant of the auxiliary cathode circuit is much smaller than that of the grid circuit so that the duration of the pulse on the grid is longer than that of the pulse on the auxiliary cathode and the turn-on effect of the grid pulse overcomes the turn-off effect of the auxiliary cathode pulse. Thus, when the tube is in a non-conducting state and a positive pulse is applied to the circuit, the tube is sent into a state of conduction.

When the tube is in the conducting state, the collection of electrons by the grid causes it to assume a negative potential. The actual measurements showed the grid to be negative when the tube is conducting by about 20 volts as compared to 3 volts in the non-conducting state. As a result, the pulses appearing on the grid have less turn-on effect when the tube is conducting than when it is non-conducting. Consequently, the circuit can be adjusted so that when the tube is in the conducting state, the turn-off effect of the auxiliary cathode pulses is larger than the turn-on effect of the grid pulses, and the tube is sent into the non-conducting state. Thus, the tube can be sent into alternate states of conduction and non-conduction by a succession of positive pulses.

Regardless of the explanations for the operation of the embodiment of the circuit shown in Figure 3 of the drawing, the circuit has been actually constructed and operates exactly as described. As an example of the circuit component values required for one embodiment of the invention and not to be construed as a limitation of the invention, the following component values are provided:

Resistor 24, 5,000 ohms
 Resistor 59, 33,000 ohms
 Resistor 56, 220,000 ohms
 Potentiometer 46, 2,500 ohms
 Condenser 48, 0.25 mmf.
 Condenser 54, 0.25 mmf.
 Battery 44, 90 volts
 Battery 23, 16 volts
 Input pulse amplitude, 45 volts

From the above description, it will be seen that a novel, useful, bistable trigger circuit, which is responsive to pulses of single polarity to successively go from one stable state to a second stable state, has been described.

What is claimed is:

1. A bistable state circuit comprising a gaseous electron tube including an anode, a control grid, a main cathode, an auxiliary cathode and a constricting electrode enclosing said auxiliary cathode and having an opening opposite said main cathode, means to apply between said main cathode and anode a first potential having a value less than the ionization potential of said tube gas, means to apply between said auxiliary cathode and said main cathode a second potential having a value between the ionizing and extinction potential of said tube gas, and means to apply successively pulses of one polarity to said main cathode, said control grid and said auxiliary cathode

to render said tube alternately conducting and non-conducting responsive to said successive ones of said pulses.

5 2. A bistable trigger circuit comprising a gaseous electron tube having a plurality of electrodes including an anode, a control grid, a main cathode, an auxiliary cathode and a constricting electrode enclosing said auxiliary cathode and having an opening opposite said main cathode, means to apply between said main cathode and anode a first potential having a value less than the ionization potential of said tube gas; means to apply between said auxiliary cathode and said main cathode a second potential having a value between the ionizing and extinction potential of said tube gas, and means including a differentiating circuit connected between said main cathode and one of said other electrodes to apply pulses of one polarity between said main cathode and said one of said other electrodes to render said tube alternately conducting and non-conducting responsive to successive ones of said pulses.

20 3. A bistable state trigger circuit comprising a gaseous electron tube including an anode, a control grid, a main cathode, an auxiliary cathode and a constricting electrode enclosing said auxiliary cathode, and having an opening opposite said main cathode, means to apply a potential having a value less than the ionization potential of the gas in said tube between said main cathode and anode, means to apply between said main and auxiliary cathodes a potential having a value between the ionization and extinction potential of the gas in said tube, a pair of pulse input terminals, a differentiating circuit coupling said input terminals to said main and auxiliary cathodes, and means coupling said control grid to one of said pair of input terminals, whereby a successive application of negative pulses to said pulse input terminals renders said tube alternately conducting and non-conducting.

25 4. A bistable state trigger circuit comprising a gaseous electron tube including an anode, a control grid, a main cathode, an auxiliary cathode and a constricting electrode enclosing said auxiliary cathode, and having an opening opposite said main cathode, means to apply a potential having a value less than the ionization potential of the gas in said tube between said main cathode and anode, means to apply between said main and auxiliary cathodes a potential having a value between the ionization and extinction potential of the gas in said tube, a pair of pulse input terminals, said main cathode being connected to one of said terminals, a condenser connected between said auxiliary cathode and the other of said terminals, a resistor connected between said pair of terminals, and means coupling said control grid to one of said pair of terminals.

30 5. A bistable trigger circuit comprising a gaseous electron discharge tube including an anode, a control grid, a main cathode, an auxiliary cathode and a constricting electrode enclosing said cathode and having an opening opposite said main cathode, means to apply a potential having a value less than the ionization potential of the gas in said tube between said anode and main cathode, means to apply between said main and auxiliary cathodes a potential having a value between the ionization and extinction potentials of the gas in said tube, a pair of pulse input terminals, said main cathode being connected to one of said pair of terminals, a first condenser connected between said auxiliary cathode and the other of said terminals, a first resistor connected

across said pair of terminals, a second condenser connected between said control grid and said other of said pair of terminals, and a second resistor connected between said control grid and said main cathode, whereby a successive application of positive pulses to said pulse input terminals renders said tube alternately conducting and non-conducting.

6. A bistable trigger circuit comprising a gaseous electron discharge tube including an anode, a control grid, a main cathode, an auxiliary cathode and a constricting electrode enclosing said cathode and having an opening opposite said main cathode, means to apply a potential having a value less than the ionization potential of the gas in said tube between said anode and main cathode, means to apply between said main and auxiliary cathodes a potential having a value between the ionization and extinction potentials

of the gas in said tube, a pair of pulse input terminals, said main cathode being connected to one of said pair of terminals, a first condenser connected between said auxiliary cathode and the other of said terminals, a first resistor connected across said pair of terminals, and a second resistor and a second condenser connected in parallel between said control grid and said main cathode whereby a successive application of negative pulses to said pulse input terminals renders said tube alternately conducting and non-conducting.
